UNITED STATES PATENT OFFICE

LUDWIG ROSENSTEIN, OF SAN FRANCISCO, CALIFORNIA, ASSIGNOR TO GREAT WESTERN ELECTRO-CHEMICAL COMPANY, OF SAN FRANCISCO, CALIFORNIA, A CORPORATION OF CALIFORNIA

METHOD FOR PRODUCING ALKALI METAL XANTHATES

No Drawing.

Application filed November 12, 1924. Serial No. 749,558.

This invention relates to a method for the manufacture of alkali metal xanthates; and its object is to produce these compounds in considerable quantities upon a commercial basis.

Another object of the invention is to make use of a closed receptacle in one step of the process to more effectively combine the alkali metal hydroxide used with the alcohol as well as to prevent the loss of alcohol at the temperature necessary to most effectively make said combination.

Another object of the invention is to provide a method for the production of alkali metal xanthates which will effectively complete the reaction with substantially the theoretical amounts of the various substances used, and with the minimum loss of material due to incompletely reacted.

The method which is the subject of this invention aims to bring about reaction between the components in nearly theoretical amounts and to produce the xanthates largely in the solid form at once. This is accomplished by first bringing about a reaction between an alkali metal hydroxide such as potassium hydroxide with commercial alcohol by heating the two together in a closed vessel from which no alcohol can escape as vapor.

Under these conditions a pressure is naturally built up, the magnitude of which depends on the temperature to which the heating is carried, and the proportion of alcohol employed to a unit weight of the alkali metal hydroxide. Under the conditions described a reaction probably takes place between the alkali metal hydroxide and the alcohol to form water and some alkali metal ethylate, but this reaction will not proceed to completion.

When the ingredients in the above described closed vessel are now cooled they will be found to consist of a semi-solid mass containing some alkali metal ethylate, alkali metal hydroxide with both water and alcohol of crystallization and a solution of the alkali metal hydroxide in any excess of alcohol originally employed.

The process is not concerned with the completeness of the alcohol plus alkali metal hydroxide reaction more than to note that

when the hydroxide is completely mechanically disintegrated with the proper amount of alcohol that the carbon bisulphide reaction will proceed smoothly and rapidly to completion in a way that is commercially practicable. In fact it is not possible to correctly determine just what is produced by this first reaction, except that the bulk of the alkali while unchanged in composition has been so changed physically as to readily react with the carbon bisulphide in the next step.

The mass above described when mixed with the proper amount of carbon bisulfide, reacts smoothly and with considerable heat evolution to form alkali metal xanthate, largely in a solid form. The separation and drying of the crystals thereof may then be carried out in any well known manner.

Since the purpose of this invention is to bring about the reaction which leads to the formation of alkali metal xanthates between substantially the theoretical quantities of reagents it is best practiced by placing in the above described closed vessel for each kilogram molecular weight of alkali metal xanthate one kilogram molecular weight of the alcohol to be used. A larger amount of alcohol than in the above proportion is often found convenient since it makes a mass more fluid and easier to stir, but in this case the excess of alcohol over the ratio above named is removed by distillation after the mass has been heated under pressure as described, and before adding the carbon bisulfide.

The alkali metal hydroxide may be finely ground for convenience as this hastens its dissolution, or it may be introduced as flake, or even in a molten condition, the essential point being that it is first brought into combination with an alcohol in the proportion of the molecular weights by the utilization of heat and pressure.

One example of a practical method of carrying out this invention is as follows:

To 60 kilograms of ground caustic potash contained in an autoclave is added 55 kilograms of commercial denatured ethyl alcohol. The autoclave is now heated with the vent cock open until alcohol vapors escape therefrom which indicates that the air has

been completely displaced. The vent cock is now closed and heat applied until the pressure reaches about 150 lbs. It is held at this pressure for one and one-half hours, after which the heat is shut off and the autoclave cooled until the mass contained in it is barely fluid enough to move. To it is then added, with stirring and cooling, 80 kilograms carbon bisulfide. When the reaction forming xanthate is completed the mass is spun dry in a centrifugal machine, and the crystals of potassium xanthate dried or further purified. There will be obtained about 145 kilograms of commercial potassium xanthate.

16 The temperature of the reacting mass when the carbon bisulphide is added should be kept below the atmospheric boiling point of the bisulphide.

20 What I claim is as follows, but modifications may be made in carrying out the invention as defined by the annexed claims:

25 1. A method of producing alkali metal xanthate which consists of heating an alkali metal hydroxide with an excess of alcohol in a closed system at a temperature capable of producing a pressure of about 150 pounds to the square inch, maintaining said pressure for a period of time to cause the substantial disintegration of the hydroxide by the alcohol, cooling the mass and then adding carbon bisulfide thereto.

35 2. A method of producing alkali metal xanthates which consists in heating an alkali metal hydroxide and an alcohol in a closed system at a temperature capable of producing a pressure of substantially 150 pounds to the square inch, maintaining that pressure and temperature for a period of time to cause the substantial disintegration of the hydroxide by the alcohol, cooling the mass, then adding carbon bisulphide thereto and finally drying the xanthate product.

40 3. A method of producing alkali metal xanthates which consists in placing an alkali metal hydroxide in a closed system with an excess of alcohol, heating the material to a temperature capable of producing a pressure above atmospheric for a sufficient time to effect a reaction of the materials and to disintegrate the hydroxide, removing the excess of alcohol by distillation, cooling the mass, adding carbon bisulfide thereto, while maintaining the mass below the decomposition point of the xanthate to be produced.

45 5. A method of producing alkali metal xanthates which consists in placing an alkali metal hydroxide in a closed receptacle with an excess of alcohol, heating the material until a temperature capable of producing a pressure of about 150 lbs. to the square inch is produced, maintaining that pressure and temperature until the disintegration of the alkali metal hydroxide is complete, removing the excess alcohol by distillation, cooling the mass, adding carbon

bisulfide thereto, maintaining the mass at a temperature below the decomposition point of the xanthate to be produced then drying the solid alkali metal xanthate produced.

5. A method of producing alkali metal xanthates which consists in dispersing an alkali metal hydroxide in an alcohol with the formation of an alcoholate, and thereafter adding carbon bisulfide to the mass while maintaining the mass at a temperature suitable for the completion of the reaction, and including the step of subjecting ingredients to pressure in a closed system during a portion of the reaction thereof.

In testimony whereof I have hereunto set my hand this 8th day of November A. D. 1924.

LUDWIG ROSENSTEIN.
